**FORMATION TEST TOOL PACKER
SETTING TOOL**

Fennion F. Moore, Carrizo Springs, Tex.

Application September 25, 1956, Serial No. 611,935

4 Claims. (Cl. 166—185)

In making tests at different levels within an oil well, the conventional practice is to lower a formation test tool, which can be of various types. The test tool includes a packer of rubber or other resiliently expansible material, which packer at a selected level is expanded into engagement with the wall of the hole so that fluid to be tested will be drawn from the portion of the hole below the packer, without intermixing with fluid above the packer. In some instances, a "straddle test" is made, utilizing two packers, spaced vertically within the hole, for the purpose of testing fluid confined in the space between the two packers.

Heretofore, to set or expand the packer, it has been necessary to use various expedients which have not proved satisfactory. In some instances, wall hooks are used, or other anchoring means. In other instances, a tail pipe is used, extending to the bottom of the hole. The use of a tail pipe is not fully satisfactory, since it prevents the swift and accurate locating of the packer at different levels within the hole, or the changing of the levels at which the packer is set, during the making of a succession of tests.

Further, any apparatus such as a wall hook, that engages in the wall of the hole is unsatisfactory, due to the fact that there is a tendency of the entire structure to slide down the hole.

It has been proposed, in this regard, to utilize a formation test tool for the purpose of making tests at selective zones within the hole, said tool to test at any level without the aid of a tail pipe. However, such a tool employs dogs, that hook into the wall of the hole and here again, the tendency of the tool to slide down the hole arises. Further, the use of dogs of this type involves the use of wall springs, for the purpose of setting the dogs, and this tends to disable the structure, so far as rotation of the drill pipe is concerned when the structure is being pulled from the hole.

The tendency of tools previously devised to slide down the hole arises from the fact that the weight of the drill pipe itself is used to set the packer.

The main object of the present invention, in view of the difficulties which have heretofore arisen, is to provide a tool for setting the packer of a formation test tool that will operate without the use of wall hooks or other anchoring devices, without the use of a tail pipe, without means that would tend to prevent rotation of the drill pipe when the tool is being removed from the hole, and without necessity of employing the weight of the drill pipe to set the packer.

Another object of importance is to provide a packer setting tool for formation test assemblies, so designed as to permit the setting of the packer with maximum speed and ease, and further designed to permit the contraction or unsetting of the packer with equal facility.

A further object is to provide a tool of the type referred to, designed to set the packer through the use of the hydrostatic head pressure already needed for the purpose of making the necessary tests. Heretofore, although a

2

hydrostatic head pressure has been needed in the use of formation tests assemblies, said pressure has not been employed for the purpose of setting the packer of the assembly.

5 Still another object is to provide a device of the character referred to that can be employed in connection with any of various test tools already in use with little or no modification of said testing tools.

Other objects will appear from the following description, 10 the claims appended thereto, and from the annexed drawing in which like reference characters designate like parts throughout the several views and wherein:

Figure 1 is a longitudinal section through a formation testing device packer setting tool formed according to the 15 present invention, connected to the formation testing device and to the packer associated with said device, a packer-expanding piston being shown in its retracted position and the packer being fully contracted, the several parts appearing as they would on lowering of the tool into 20 a hole preliminary to setting of the packer;

Figure 2 is an enlarged, longitudinal section through the packer setting tool constituting the present invention, the formation test device and packer being broken away;

Figure 3 is a longitudinal section on the same scale 25 as Figure 2, showing the formation test device and packer with the piston extended and the packer set against the wall of the hole;

Figure 4 is a longitudinal section showing the lower portion of the packer setting tool constituting the present invention and the upper portion of the formation test device, 30 with the piston advanced;

Figure 5 is a section on line 5—5 of Figure 3;

Figure 6 is a section on line 6—6 of Figure 2;

Figure 7 is a section on line 7—7 of Figure 3;

Figure 8 is a section on line 8—8 of Figure 3;

Figure 9 is a section on line 9—9 of Figure 2;

Figure 10 is a section on line 10—10 of Figure 1;

Figure 11 is a section on line 11—11 of Figure 14;

Figure 12 is a fragmentary elevational view showing 40 the rotatable connection between the packer setting means and the formation test device;

Figure 13 is a section on line 13—13 of Figure 12; and

Figure 14 is a longitudinal section showing the portion 45 of the formation test device in which the piston is mounted, the piston being in its advanced position and the device being rotated to permit escape of pressure fluid past the piston for equalizing the pressure on both sides thereof to permit contraction of the packer.

Referring to the drawings in detail, 10 designates a 50 drill pipe which would extend to the top of the hole. The formation test device packer setting tool constituting the present invention has been generally designated at 11 and is connected to a conventional formation test device generally designated 13.

The tool constituting the present invention includes an 55 outer casing 12 of cylindrical formation, having a threaded tool joint connection at its upper end to the lower end of the drill pipe 10. Formed in outer casing 12 (Figure 1) is a threaded axial bore, and threadedly engaged in the bore is a housing 14 of inverted 60 cup shape for a vertically shiftable, axially disposed disc breaker bar or plunger 16. The closed, upper end of housing 14 has a center opening in which the plunger 16 is slidably engaged intermediate the ends of the plunger. Engaged in the center opening (Figures 1 and 65 10) is an O-ring 18 sealably bearing against the plunger 16.

The upper end of the plunger has a head 20, disposed 70 within the drill pipe 10. Normally the plunger is in its upper position shown in Figure 1. However, a bar 21 (Figure 2) may be lowered from the surface within the drill pipe 10, to engage the head 20, for the pur-

pose of shifting the plunger downwardly to its lowered, Figure 2 position. In this position, the head 20 engages against the closed, upper end of plunger housing 14. Head 20 is threaded onto the upper end of the elongated body of the plunger 16, and may be locked in position by a set screw 22 (Figure 2) if desired. This, however, is not essential. The head could be integral with the elongated body of the plunger.

At its lower end, the plunger is provided, within housing 14, with a tapered or pointed head 26.

Formed in the wall of the plunger housing intermediate the ends of the plunger housing is a pair of diametrically opposed ports 28, the purpose of which will be made presently apparent. These ports are in communication with the upper ends of diametrically opposed longitudinal passages 30 formed in casing 12, the passages 30 opening at their lower ends into a passage 31 extending diametrically of the casing 12.

The casing 12 has an axially extending chamber 32, and opening into said chamber are diametrically opposed, radially extending inlet ports 34. The mud or fluid in the hole is adapted to enter the device through the inlet ports 34, that is, the mud or fluid surrounding the device passes into the chamber 32 through these inlet ports, filling the chamber below a frangible disc 36 separating chamber 32 from the interior of the plunger housing 14.

Therefore, when bar 21 is dropped, the plunger 16 will be shifted downwardly from its Figure 1 to its Figure 2 position. The pointed head 26 thereof will pass through the frangible partition or disc 36, breaking the same as shown in Figure 2. Therefore, the mud or fluid that has filled the chamber 32 is now free to pass upwardly into the interior of the plunger housing 14. Said fluid then passes through the ports 28 into the longitudinal passages 30, and then into the diametrically extending passage 31.

Angularly spaced 90 degrees from the respective longitudinal passages 30, within the casing 12, are longitudinal passages 38. These open at one end into the drill pipe above the plunger housing 14. At their lower ends, they open into communication with a passage provided in the formation test setting device, for the purpose of carrying the test fluid back to the surface. These passages are shown in dotted lines in Figures 1 and 2; they are also shown in full lines in Figure 4, because Figure 4 is a longitudinal section in which the cutting plane is at right angles to the plane of Figures 1 and 2.

In the lower end of casing 12 there is formed a threaded opening and engaged in said opening is the upper end of a tube 40. This extends axially of casing 12 beyond the externally threaded or male lower end of the casing 12. Tube 40 at its upper end communicates with the diametrical passage 31.

The formation test device 13 is per se conventional, and a typical device of this type is shown. The packer setting tool constituting the invention can be used either with the test device 13 illustrated, or with various other test devices presently employed. If used with other test devices, the tube 40 might not follow a path axial of the test device, but instead may follow a different path, it being mainly important that it be connected at its lower end in communication with the test fluid passages of the testing device.

The formation testing device 13 includes a casing 42 connected to the lower end of casing 12. In casing 42 there are formed upwardly converging passages 44 communicating with the lower end of tube 40. Passages 44 at their lower, divergent ends communicate with longitudinal, diametrically opposed passages 46 of device 13.

In the casing 42, below the divergent ends of passages 44, an axially extending chamber 47 is provided. This has diametrically opposed grooves 48 (Figures 1

and 4) formed in its wall. Passages 46 are passages through which pressure fluid is forced for advancing a piston slidably within chamber 47. Passages 48 are angularly spaced 90 degrees from the respective passages 46.

The piston has been designated at 50 and is shown in retracted position in Figure 1 and in advanced position in Figures 3, 4, and 14. The piston has a center opening, receiving an axial tube 52 mounted in the casing 42. Tube 52 is engaged at its upper end in a recess formed at the upper end of the chamber 47 and communicating with said recess are passages 54 (Figure 4) for the test fluid, said test fluid flowing upwardly through the tube 52.

To prevent leakage between tube 52 and the axial bore formed in piston 50 for receiving the tubes, O-rings 56 are mounted in the wall of the piston bore surrounding tube 52.

In the piston there are provided diametrically opposed passages 58, the upper ends of which communicate with radial passages 60 opening upon the outer wall of the piston 50. At their lower ends, passages 58 communicate with the lower ends of passages 46. Therefore, pressure fluid traveling downwardly through passages 46 will move into the passages 58 and will force the piston upwardly within chamber 47 from its Figure 1 to its Figure 4 or 14 position.

Integral with the piston and extending axially within the formation test casing is an elongated, axially bored stem 62. Stem 62 and piston 50, and also tube 52 constitute a part of the packer setting tool 11, rather than a part of the formation test device 13.

Stem 62 projects downwardly a substantial distance, through an axial bore of a block 64 having a threaded connection at its upper end to the lower end of the casing 42 of the formation test device 13. At the lower end of block 64 there is provided a ball race 66 (Figures 1 and 13), and below the ball race is a support body 68 for a packer.

At the lower end of block 64 there is provided a depending tongue 70 extending circumferentially of block 64 (Figure 13) through approximately 90 degrees. This is disposed in a circumferentially extending slot 72 of body 68, said slot extending through 180 degrees. The support body 68 and block 64 are thus relatively rotatable through 90 degrees.

A packer 74 is per se conventional, and is radially expandable into engagement with the wall of the well hole. Below the packer there is provided bottom block 76, axially bored in communication with stem 62 and formed with a threaded recess in which the lower end of stem 62 is engaged.

Referring to Figure 3, the packer is shown expanded into engagement with the wall 78 of the well hole 80, so that a fluid test can be made at a level below the packer.

In use, and assuming that a test is to be made at a particular level within the hole, the entire device, appearing as in Figure 1, is lowered into the hole so that the inlet to the bore of bottom block 76 is at the desired level.

Then bar 21 is dropped from the surface and strikes the plunger 16, forcing the plunger through frangible disc 36.

At this time, the mud or fluid hole will have entered the chamber 32 through ports 34. The pressure within chamber 32 may be varied according to the depth of the hole and the weight of the fluid therein.

On breaking of disc 36, hydrostatic fluid, as previously noted in this description, will now be free to flow upwardly into the plunger housing 14. Said fluid passes through ports 28 and then down through passages 30 into passage 31, thereafter travelling downwardly within tube 40, to pass through the test tool 13. As the fluid passes out of the tube 40 it moves downwardly through divergent passages 44 (see Figure 1) and then down through passages 46. Fluid then moves upwardly within passages

58 of the piston 50 and exerts pressure upon the piston shifting the same upwardly to the Figure 3 position thereof. This is due to the fact that as of this moment, the fluid cannot escape through the radial ports 60 of the piston, since these ports are closed by the wall of the piston chamber during the setting of the packer 74.

Upward movement of the piston will cause the packer to be expanded from its Figure 1 to its Figure 3 position.

The test tool is now ready to be opened. The test fluid moves forwardly through bottom block 76, stem 62, 10 into tube 52 (see Figure 4). Leaving tube 52 the test fluid travels upwardly in Figure 4 through the upwardly divergent passages 54 of test tool casing 42. Thereafter, the fluid flows about tube 40 upwardly within the lower 15 end of casing 12 of the invention and now travels upwardly through passages 38 of casing 12 which, as previously noted, are angularly spaced 90 degrees from the passages 30 of this casing (see Figure 6). Leaving passages 38, the fluid travels upwardly within the drill pipe 10 to the surface.

After the test has been obtained and the packer is to be collapsed, the drill pipe is rotated. The packer remains stationary since it is tightly engaged against the wall of the drill hole.

Rotation of the drill stem will cause rotation of block 64 relative to the packer. Said rotation is through 90 degrees, as previously described (see Figure 13).

Since bottom block 76 is fixedly connected to the piston through the medium of the elongated stem 62, and is further connected to the packer against rotation relative to the packer, the piston 50 will not rotate when the block 64, test tool 13, and packer setting tool 11 are rotated with the string of drill pipe.

Therefore, and referring now to Figure 14, ports 60 become aligned with the longitudinal grooves 48 formed in the wall of the piston chamber.

Therefore, the hydrostatic head of pressure bearing against the underside of the piston within passages 58 is equalized above the piston within the piston chamber. This is so because said pressure now escapes through ports 60 and grooves 48 into the portion of the chamber above the piston.

Since the pressure is equalized both above and below the piston the packer now returns to its original, contracted condition shown in Figure 1 to permit retrieving of the entire device from the hole.

The device would of course be slightly modified when used with test tools other than the particular one shown. Tube 40, for example, may comprise more than one tube, it being mainly important that it discharge the functions previously described herein of permitting hydrostatic fluid pressure to be directed from the test tool to below the piston for advancing the piston.

Further, it will be understood that the collapsing pressures required on the packer will be varied according to the particular situation, with said pressure being determined according to the depth in which the test is to be made, the pressure of the mud, and the size of the piston. All these calculations are well known per se and can be readily made by those working in the art.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles, it being considered that the invention comprehends any minor change in construction that may be permitted within the scope of the appended claims.

What is claimed is:

1. The combination, with a tool for sampling fluids from strata encountered in a well hole, and with a drill pipe for lowering said tool into the hole, of a packing and packing setting device comprising: a longitudinally con-

tractile, radially expandable packer having an upper end limited against upward movement by the lower end of said tool; a piston connected to the lower end of and extending above the packer, said tool having a cylinder in which the piston works and having a passage opening at one end into said cylinder, said cylinder having a longitudinal chamber and the piston being movable longitudinally of and within the chamber, the piston having an upper portion in wiping contact with the wall of said chamber and facing downwardly into the lower part of the chamber, said passage opening into the chamber through the wall thereof below said upper portion of the piston; a casing aligned longitudinally with and interposed between the tool and drill pipe, said casing being connected at its ends to the tool and drill pipe respectively and having a bore constituting a second passage, said second passage communicating at one end, through the wall of the casing, with a surrounding well hole space in which drilling fluid is confined under pressure, the second passage at its other end communicating with the other end of said first passage, whereby said drilling fluid, whenever permitted to enter the second passage, will flow therethrough and through the first passage under pressure to enter the lower part of the chamber and impinge against the underside of said upper portion of the piston to shift the same upwardly for radially expanding the packer; a frangible seal extending across the second passage to normally prevent the flow of the drilling fluid to the piston, the drill pipe having an axial bore communicating with said second passage; and means mounted in the drill pipe and second passage for movement against the seal to rupture the same.

2. The combination, with a tool for sampling fluids from strata encountered in a well hole, and with a drill pipe for lowering said tool into the hole, of a packing and packing setting device comprising: a longitudinally contractile, radially expandable packer having an upper end limited against upward movement by the lower end of said tool; a piston connected to the lower end of and extending above the packer, said tool having a cylinder in which the piston works and having a passage opening at one end into said cylinder, said cylinder having a longitudinal chamber and the piston being movable longitudinally of and within the chamber, the piston having an upper portion in wiping contact with the wall of said chamber and facing downwardly into the lower part of the chamber, said passage opening into the chamber through the wall thereof below said upper portion of the piston; a casing aligned longitudinally with and interposed between the tool and drill pipe, said casing being connected at its ends to the tool and drill pipe respectively and having a bore constituting a second passage, said second passage communicating at one end, through the wall of the casing, with a surrounding well hole space in which drilling fluid is confined under pressure, the second passage at its other end communicating with the other end of said first passage, whereby said drilling fluid, whenever permitted to enter the second passage, will flow therethrough and through the first passage under pressure to enter the lower part of the chamber and impinge against the underside of said upper portion of the piston to shift the same upwardly for radially expanding the packer; a frangible seal extending across the second passage to normally prevent the flow of the drilling fluid to the piston, the drill pipe having an axial bore communicating with said second passage; and a plunger mounted in the drill pipe bore and second passage for movement, under the control of a worker, against the seal to rupture the same.

3. The combination, with a tool for sampling fluids from strata encountered in a well hole, and with a drill pipe for lowering said tool into the hole, of a packing and packing setting device comprising: a longitudinally contractile, radially expandable packer having an upper end limited against upward movement by the lower end

of said tool; a piston connected to the lower end of and extending above the packer, said tool having a cylinder in which the piston works and having a passage opening at one end into said cylinder, said cylinder having a longitudinal chamber and the piston being movable longitudinally of and within the chamber, the piston having an upper portion in wiping contact with the wall of said chamber and facing downwardly into the lower part of the chamber, said passage opening into the chamber through the wall thereof below said upper portion of the piston; a casing aligned longitudinally with and interposed between the tool and drill pipe, said casing being connected at its ends to the tool and drill pipe respectively and having a bore constituting a second passage, said second passage communicating at one end, through the wall of the casing, with a surrounding well hole space in which drilling fluid is confined under pressure, the second passage at its other end communicating with the other end of said first passage, whereby said drilling fluid, whenever permitted to enter the second passage, will flow therethrough and through the first passage under pressure to enter the lower part of the chamber and impinge against the underside of said upper portion of the piston to shift the same upwardly for radially expanding the packer; a frangible seal extending across the second passage to normally prevent the flow of the drilling fluid to the piston, the drill pipe having an axial bore communicating with said second passage; and means mounted in the drill pipe and second passage for movement against the seal to rupture the same, said casing, tool, piston, and packer having communicating conduits constituting a third passage through which fluid samples may be extracted from the hole, said third passage being wholly out of communication with the first and second passages and extending into communication with the drill pipe bore from a location below the packer.

4. The combination, with a tool for sampling fluids from strata encountered in a well hole, and with a drill pipe for lowering said tool into the hole, of a packing and packing setting device comprising: a longitudinally contractile, radially expandable packer having an upper end limited against upward movement by the lower end of said tool; a piston connected to the lower end of and extending above the packer, said tool having a cylinder in which the piston works and having a passage opening at one end into said cylinder, said cylinder having a

longitudinal chamber and the piston being movable longitudinally of and within the chamber, the piston having an upper portion in wiping contact with the wall of said chamber and facing downwardly into the lower part of the chamber, said passage opening into the chamber through the wall thereof below said upper portion of the piston; a casing aligned longitudinally with and interposed between the tool and drill pipe, said casing being connected at its ends to the tool and drill pipe respectively and having a bore constituting a second passage, said second passage communicating at one end, through the wall of the casing, with a surrounding well hole space in which drilling fluid is confined under pressure, the second passage at its other end communicating with the other end of said first passage, whereby said drilling fluid, whenever permitted to enter the second passage, will flow therethrough and through the first passage under pressure to enter the lower part of the chamber and impinge against the underside of said upper portion of the piston to shift the same upwardly for radially expanding the packer; a frangible seal extending across the second passage to normally prevent the flow of the drilling fluid to the piston, the drill pipe having an axial bore communicating with said second passage; and means mounted in the drill pipe and second passage for movement against the seal to rupture the same, said tool and piston being connected for relative rotation, said upper portion of the piston having ports communicating with the lower part of said chamber, the wall of said chamber being formed with ports communicating with the part of the chamber above the upper portion of the piston, said ports of the chamber and of the piston communicating with each other in one position to which the tool is rotated relative to the piston so as to provide, in said one position of the piston, communication between the upper and lower parts of the chamber, thus to relieve pressure at both sides of the piston for longitudinally expanding the packer from said contracted condition thereof.
